UNITED STATES PATENT OFFICE

HARRY M. SALYER, OF NEW YORK, N. Y., ASSIGNOR TO LUDWIG & CO.,
OF SAME PLACE.

SELF-PLAYING ATTACHMENT FOR KEY MUSICAL INSTRUMENTS.

SPECIFICATION forming part of Letters Patent No. 653,263, dated July 10, 1900.

Application filed July 17, 1899. Serial No. 724,064. (No model.)

To all whom it may concern:

Be it known that I, HARRY M. SALYER, a citizen of the United States, and a resident of the city of New York, borough of Bronx, 5 in the county of New York and State of New York, have invented certain new and useful Improvements in Self-Playing Attachments for Key Musical Instruments, of which the following is a specification.

10 The object of my invention is to provide a new and improved self-playing attachment for key instruments—such as pianos, organs, and the like—which attachment is simple in construction, strong and durable, can easily 15 be applied on any key instrument, and plays any desired melody, according to the tune-sheet inserted, and produces all the various effects in music, such as forte and piano, works the pedals, varies the speed at which 20 the music is to be produced, and which attachment can easily be adjusted to repeat the same melody any number of times automatically or can be adjusted to stop at the end of a tune, and which attachment also rapidly 25 rewinds the music-sheet upon its original roller to permit removing it from the attachment, so that another music-roller can be inserted.

In the accompanying drawings, forming a 30 part of this specification, and in which like letters of reference indicate like parts in all the views, Figure 1 is a general plan view of my improved self-playing attachment for key instruments, the attachment being shown 35 as applied to the keyboard of a piano and the air-compressor used for working the attachment being shown in diagram. Fig. 2 is a side view of the clamping-bracket on the under side of the attachment for holding the 40 attachment over the keyboard. Fig. 3 is a vertical longitudinal sectional view of one of the key-operating plungers and the valve mechanism for the same. Fig. 4 is a detail plan view, enlarged, of the pedal-operating mechanism. Figs. 5 and 6 are enlarged vertical 45 transverse sectional views on the lines 5 5 and 6 6 of Fig. 1, respectively, both in the direction toward the right of Fig. 1. Fig. 7 is an enlarged sectional view of the key-levers, 50 taken on the line 5 5 of Fig. 1. Fig. 8 is an enlarged plan view of the music-sheet rollers

and the mechanism for operating the same, parts being broken away. Figs. 9 to 12 are sectional views of the controlling-cock. Fig. 13 is a sectional plan view of the automatically-adjustable pressure-regulating valve. Fig. 14 is a side view of the brake-pulley.

The entire mechanism is contained in a casing A, provided with a bottom A', which rests on suitable rabbits A², Fig. 1, of the keyboard-support, and from the under side of said bottom A' bracket-pieces A³ extend downward and below the keyboard-support A⁴ of the pianoforte, the brackets A³ each being provided with a screw A⁵, by means of 65 which the casing A can be clamped on the pianoforte-casing.

The casing A is provided with a hinged cover A⁶ and with an intermediate horizontal partition or floor A⁷. On the intermediate 70 floor or partition A⁷ a bridge-piece B is secured, near the longitudinal center line of the intermediate partition or floor A⁷ and in the direction of the length of the keyboard, which bridge-piece is preferably shaped conical in 75 cross-section and is provided with a flat top B', Fig. 7, in which a series of ducts or channels b terminate. Directly above the upper end of each channel b a valve B² for closing the channel is located, each attached to a 80 spring-strip B³, which spring-strips are all secured on a rail B⁴, attached to standards B⁵ at the ends of the bridge-piece B. A shaft B⁶ is secured in the upper ends of the standards B⁵, and on said shaft a key-lever C is 85 mounted for each duct or channel b in the bridge-piece B, and the downwardly-extending free end C' of each key-lever rests upon the free end of the corresponding spring-strip B³, carrying on its under side the valve 90 B² for the corresponding duct or channel b.

Each key-lever C is provided at its free end with a beveled upwardly-extending lug C², which several lugs C² each pass through a corresponding transverse slot c in a top plate C', secured to the standards B⁵, the said key-levers C being held in such positions that their lugs C² project through these slots c under the action of their corresponding springs B³. A retaining-bar C⁶, grooved longitudinally on its under side for receiving the several lugs C² of the key-levers C, is hinged to

a standard b' and at its opposite end is provided with a latch b^2 for engaging another standard b^3 for the purpose of locking said retaining-bar in place.

5 The downwardly-extending front end C' of each key-lever C is provided with an arm C^4 , extending toward the rear, and over the said several arms C^4 a half-round bar C^5 extends in such a manner that when the several key-levers are raised and the half-round bar C^5 is in such a position that its flat side is in a horizontal plane the upper edges of the several arms C^4 will rest against the said flat side of the half-round bar, as shown in Fig. 7.

15 A note-sheet of paper or other suitable material and provided with slots a' , suitably spaced and arranged according to the music to be produced, rests upon the slotted plate C^5 , on which it is held by the retaining-bar C^6 , 20 the perforations a' being arranged in parallel rows extending in the direction of the length of the note-sheet, the rows being an equal distance from each other and separated a distance equal to the distance between the 25 lugs C^2 .

25 Each music-sheet is secured to a roller D , which is mounted removably between the standard D' and the hub of a cog-wheel D^3 , mounted in a suitable standard D^4 on the intermediate floor or partition A^7 , and that end 30 of the roller D engaging the hub of the cog-wheel D^3 is squared or in any other manner so shaped as to turn with the cog-wheel D^3 . The standard D' is provided with a longitudinally-movable spring-bearing D^2 , of any well-known construction, for holding the left-hand end of the roller D in such a manner that it may turn freely, at the same time permitting the ready removal of the roller, with 35 the note-sheet thereon, when said spring-bearing D^2 is pulled out to the left. I do not show the details of the construction of this spring-bearing, nor of the ends of the pivots of roller D , as such constructions are all well 40 known and not of my invention. The other end of the note-sheet is secured in any suitable manner on the playing-roller D^5 , which is mounted in suitable bearings D^6 , Fig. 8, and is provided with means for attaching the 45 end of the note-sheet to it, such means being shown in Fig. 1 and consisting of a pin d , projecting into a slot d' in the note-sheet a ; but any other well-known contrivance may be used for securing the end of the note-sheet 50 in the playing-roller D^5 . The playing-roller D^5 carries a cog-wheel D^7 , secured to the shaft of said playing-roller D^5 , which cog-wheel D^7 can be engaged by a small cog-wheel D^8 , mounted in a free end of a swinging arm D^9 , mounted to rock on a shaft of the pinion D^{10} , which pinion engages the wheel D^7 . The shaft E , on which said pinion D^{10} is secured, is a driven shaft of a compressed-air motor E' of any suitable construction. A cog-wheel E^2 , mounted on a suitable standard, engages the cog-wheel D^7 , so that when the arm D^9 , Fig. 5, is pushed to the right the cog-wheel

D^8 engages the cog-wheel E^2 , and as the latter engages the cog-wheel D^8 on the roller D the latter will be rotated and the sheet that has been wound upon the playing-roller D^5 during the playing of the instrument can be rewound back upon the original roller D by means of the said motor. All that is necessary is to shift the cog-wheel D^8 out of engagement with the cog-wheel D^7 and into engagement with the rewinding cog-wheel E^2 . A centrifugal governor F , of any well-known construction, is provided upon its central shaft with a pinion F' , engaged by the cog-wheel F^2 on the shaft E , driven directly by the motor, and said governor F is provided with a friction-disk F^3 , which rotates with the weights and moves lengthwise on the governor-shaft when said weights swing toward or from each other. A spring-brake lever F^4 , attached to the horizontal partition A^7 , extends upward at the side of the friction or brake disk F^3 , and the friction-lever F^4 can be pressed against the friction-disk F^3 by two 90 wedges F^5 and F^6 , which can press laterally on the lever F^4 , the wedge F^6 resting against the beveled inner end part F^{10} of an elbow-lever F^7 , pivoted on a standard F^8 , its other end resting against an adjustable screw F^9 in the standard F^{11} on the partition A^7 , which screw can be turned by means of a handle F^{12} , provided with a pointer F^{13} .

The plungers for operating the keys and other parts of the mechanism, and which are all of one and the same construction and clearly shown in section in Fig. 3, will now be described. Compressed air is conducted into a chamber G , with which one or more of said plungers may be connected. The piston in the cylinder H^2 is provided with a suitable packing H^1 , and a piston-rod H^3 , secured to the piston, extends through a hole in the outer head of the cylinder, whereby the piston-rod is guided. Said piston-rod may operate any suitable mechanism or it may carry a head H^4 for striking a key, and which head is provided with a rubber, felt, or other pad H^5 . The outer head of the cylinder is provided with a vent-aperture H^6 , and a helical spring H^7 , surrounding the piston-rod H^3 , serves for pressing the piston inward. At the inner end of the cylinder H^2 and between the same and the chamber G a cylinder J is located, the axis of which is at right angles to the axis of the cylinder H^2 , and this cylinder J contains a piston J' , provided with a suitable packing J^2 , a helical spring J^3 being interposed between the cylinder-head J^4 and the piston J' and bearing on each. An apertured neck J^5 in the cylinder-head J^4 is connected by a fine air-tube n with one of the channels b in the bridge-piece B for a purpose that will appear hereinafter. The piston-rod K of the piston J' is made hollow and is adapted to work freely through the central axial bore K' of a hub K^1 , fixed in the cylinder J , which hub is provided with a duct K^2 , extending from the center bore K' to the inner
